UNITED STATES PATENT OFFICE.

JAMES F. SAYER, OF MACOMB, NEW YORK.

IMPROVEMENT IN STAVE-JOINTERS.

Specification forming part of Letters Patent No. 57,387, dated August 21, 1866.

To all whom it may concern:

Be it known that I, JAMES F. SAYER, of Macomb, in the county of St. Lawrence and State of New York, have invented a new and useful Improvement in Stave-Jointers; and I do hereby declare that the following is a full and exact description thereof, reference being had to the accompanying drawings, making part of this specification.

Figure 1 is a perspective view of my improved apparatus; Fig. 2, a cross-section of the same.

Like letters of reference indicate corresponding parts in both figures.

My invention consists in the special arrangement of the apparatus whereby the stave is clamped to the bed in the form it assumes in a barrel. A knife or cutter runs over its edge to remove the rough, and a plane then smoothes it down.

As represented in the drawings, A is a bed having a curved side, *a*, for fitting the stave thereto, and a level surface, *b*, for the action of the plane. The curve of the side *a* is made to conform to that of the barrel, both longitudinally and transversely. At one extremity is a socket, *d*, to receive one end of the stave *c*, and at the other a clamp-head, *f*, jointed at *g* to a bearing, *h*. This head is made curved on the inside, to correspond with the side *a*, and it is opened or closed by a handle, *i*. One end of the stave is placed in the socket *d*, and the clamp-head is then closed on the other end, as shown in black lines, Fig. 1, when the stave is ready to be jointed.

Midway of the bed is a bearing, *k*, to which is jointed a knife, *B*, by means of a bolt, *l*, or equivalent. This knife is provided with a handle, *m*, and double cutting-edges *n n*. It moves over the edge of the stave from the cen-

ter each way, as shown in dotted and red lines, so as to cut only with the grain. When the rough edge of the stave has been cut down so as to fit it for smoothing, the knife is thrown around out of the way, as in red lines, and the plane *C* is driven over the bed, and perfectly joints the edge. In order to guide the plane properly it has a vertical tongue, *p*, that runs in a longitudinal groove, *r*, of the bed.

The apparatus above described combines simplicity with effectiveness, and recommends itself particularly to barrel manufacturers who do not have the advantages of power. Staves can be jointed very rapidly and in a perfect manner. The stave is inserted and bent to the form it assumes in a barrel in a moment's time by simply closing the clamp-head *f*. A sweep of the knife *B* in each direction from the center cuts off the rough without running against the grain, and a few strokes of the plane completes the operation. The edge, when jointed, fits accurately, since the form is the same as in the barrel.

I am aware that staves have before been secured to a bed in the curved form they assume in the barrel, and then jointed by means of circular saws or cutters; but such, broadly, I do not claim.

What I claim as my invention, and desire to secure by Letters Patent, is—

The double-acting knife *B*, in combination with the table having the curved side *a*, groove *r*, plane *C*, and clamp *f* attached, when constructed to operate substantially as described and for the purposes set forth.

JAMES F. SAYER.
